US0D1109724S

(12) **United States Design Patent** (10) Patent No.: **US D1,109,724 S**
(45) Date of Patent: ** Jan. 20, 2026

(54) **MOBILE PHONE CASE**

(71) Applicant: **Electronic Silk Road (Shenzhen) Tech Co., Ltd.**, Shenzhen (CN)

(72) Inventor: **Jie Xiang**, Guangdong (CN)

(**) Term: **15 Years**

(21) Appl. No.: **35/522,839**

(22) Filed: **Sep. 26, 2024**

(80) **Hague Agreement Data**

Int. Filing Date: **Sep. 26, 2024**

Int. Reg. No.: **DM/241288**

Int. Reg. Date: **Sep. 26, 2024**

Primary Examiner — L. A. Grabenstetter

(57) **CLAIM**

The ornamental design for a mobile phone case as shown and described.

DESCRIPTION

FIG. 1.1 is a front elevational view of a mobile phone case showing our new design;

FIG. 1.2 is rear elevational view thereof;

FIG. 1.3 is a left side elevational view thereof;

FIG. 1.4 is a right side elevational view thereof;

FIG. 1.5 is a top plan view thereof;

FIG. 1.6 is a bottom plan view thereof;

FIG. 1.7 is a front, bottom and right side perspective view thereof;

FIG. 1.8 is a rear, bottom and left side perspective thereof;

FIG. 1.9 is an exploded perspective view thereof; and

FIG. 1.10 is another exploded perspective view thereof.

The broken lines in the drawings depict portions of the mobile phone case that form no part of the claimed design.

1 Claim, 10 Drawing Sheets
